[57] CLAIM

The ornamental design for a display package for dispensing tubes, as shown and described.

DESCRIPTION

FIG. 1 is a front elevational view of a display package for dispensing tubes showing my new design; the rear elevational view being a mirror image thereof;
 FIG. 2 is a left side elevational view thereof, the right side elevational being a mirror image thereof;
 FIG. 3 is a bottom plan view thereof; and,
 FIG. 4 is a top plan view thereof.
 The broken line showing of caulking tubes is for illustrative purpose only and forms no part of the claim.

FIG. 4

FIG. 1

FIG. 2

FIG. 3
